[57] CLAIM

The ornamental design for a snowmobile track, as shown and described.

DESCRIPTION

FIG. 1 is a side elevational view of the snowmobile track showing my new design with the break lines being indicative of indeterminant length;

FIG. 2 is a plan view of the section of snowmobile track indicated by the arrows 2—2 in FIG. 1;

FIG. 3 is a perspective view of a section of the snowmobile track as seen from the left hand side and upper end of FIG. 2;

FIG. 4 is a cross-sectional view taken on the line 4—4 in FIG. 3 in the direction of the arrows;

FIG. 5 is a somewhat enlarged planned view of a section of the track, the bottom view being a mirror image thereof;

FIG. 6 is a sectional view taken on the line 6—6 in FIG. 5 in the direction of the arrows;

FIG. 7 is a view as seen in the direction of the arrows 7—7 in FIG. 5;

FIG. 8 is a view corresponding to FIG. 5 but showing a slightly modified form of track, the bottom view of which is a mirror image thereof; and,

FIG. 9 is a view as seen in the direction of the arrows 9—9 in FIG. 8.
